UNITED STATES PATENT OFFICE.

CHARLES W. KECKLER, OF NEWARK, NEW JERSEY, ASSIGNOR TO WESTERN ELECTRIC COMPANY, INCORPORATED, OF NEW YORK, N. Y., A CORPORATION OF NEW YORK.

TELEPHONE SYSTEM.

1,387,271.

Specification of Letters Patent.

Patented Aug. 9, 1921.

Application filed March 27, 1918. Serial No. 224,924.

To all whom it may concern:

Be it known that I, CHARLES W. KECKLER, a citizen of the United States, residing at Newark, in the county of Essex, State of New Jersey, have invented certain new and useful Improvements in Telephone Systems, of which the following is a full, clear, concise, and exact description.

This invention relates to telephone systems, and more particularly to trunking arrangements used between an intercommunicating system and an exchange.

The principal object of the present invention is to provide a new and improved trunking arrangement between a plurality of associated stations and an outside station or exchange in which the trunk circuit can be held in substitution of a telephone set. In accordance with this feature of the invention, a locally energized electromagnetic means is provided to establish a bridging connection with the trunk circuit, together with means to include and maintain said electromagnetic means energized over such bridging connection after establishment thereof.

Other objects and features of the invention will appear from consideration of the following description.

30 The drawing illustrates one embodiment of the present invention as applied to an intercommunicating system. There are shown three intercommunicating stations, each being provided for service over a trunk line 35 common thereto leading to an exchange at which the jack 10 and answering signal 11 of the trunk are located.

The intercommunicating stations A, B and C are shown as provided with a transmitter 40 12, receiver 13, hook switch 14, signal 15 and impedance coil 16, through which talking current from battery 17 is supplied to the telephonic apparatus of its station. A set of keys is provided at each station to connect 45 with other stations of the system and such stations as are equipped for trunk service will have a trunk key T, and will also have a retaining key R if such station is also intended to be able to transfer a trunk call to 50 other stations of the system having trunk service. The keys operate through a locking plate 18 which locks any depressed key, except the retaining key R in intermediate position until released by the depression of

another of the keys A, B, C, H or T. The 55 key R is not locked by the plate 18, and does not release any other keys in its operation. It is normally open as shown, but when operated, it effects the holding of the trunk circuit, as hereinafter explained. The remaining keys, with the exception of the trunk keys T and home keys H, have three positions: the normal, as shown, the signaling or lowermost position in which the first and second, and third and fourth contacts are 60 engaged and in which the third contact engages the bus bar 19; and an intermediate position, which differs from signaling position only in that there is no engagement of the contacts of these keys with the bus bar 65 19. The trunk keys T and home keys H differ in that they need have only a normal and talking position, it being unnecessary for any of its contacts to engage the bus bar 70 19. The plate 18 serves to lock any depressed key in intermediate position until 75 released by operation of another of their number.

The present invention will best be understood from a description of the actual operation in handling a trunk call. For this purpose assume that the exchange operator has connected an outside line to the jack 10 and applied exchange signaling current to operate the signal 20. This signal is preferably located close to one of the intercommunicating stations, which it is desired to have answer trunk calls in general. As shown, this is station A; and the party thereat, upon perceiving that the signal 20 80 has operated, will depress his trunk key T to intermediate position and remove his receiver 13 from the hook switch 14, thereby bridging that station across the conductors 21, 21' of the trunk line. Talking current 85 for the trunk connection is supplied by a talking battery at the exchange (not shown) on plugging into the jack 10, and completes the talking circuit to station A on removal of the receiver and depression of key T 90 95 thereat. This circuit extends from talking battery (not shown) over the ring contact 22 of jack 10, exchange end of conductor 21', winding of relay 23, conductor 24, winding of relay 25, conductor 21', 26, first and second contacts of key T, conductors 27 and 28, transmitter 12, receiver 13, hook switch 14, conductors 29 and 30, fourth and third con-

tacts of key T, conductors 31 and 21 to the tip contact 32 of jack 10 and thence to the other side of talking battery. The relay 25 is preferably made slower acting than relay 23 so that on closure of this circuit the relay 23 will operate to close a short-circuiting path about the relay 25 before the latter can operate. This short circuit starts at conductor 24, and extends through armature and alternate contact of relay 23 and conductor 33 to conductor 21' beyond relay 25. The relative speed of these two relays is not however absolutely essential, since even should relay 25 operate first, relay 23 would still operate and on attracting its armature short-circuit relay 25, thereupon allowing it to return to normal position. Station A would thus be in talking connection with the outside line and could converse therewith. At the conclusion of the conversation, the party at station A, restoring the receiver to its switchhook, opens the alternate switchhook contact, thereby operating a disconnect signal associated with the connected cord circuit at the exchange as is usual in common battery exchange systems.

Should party A find station B was desired, he would depress his retaining key R, thereby completing an actuating circuit for the holding relay 34. This circuit extends from signaling battery 35 of the intercommunicating system, conductors 36 and 37, bus bar 19, contacts of key R, conductors 38 and 39, right-hand winding of relay 34, conductors 40 and 41 to the other side of battery 35. Relay 34 is thereby operated and closes a holding circuit across the trunk line 21 and 21' which derives its energizing current from the talking battery of the exchange at which the jack 10 is located. This circuit extends from conductor 21' before it reaches relay 23, and extends over conductor 42, front armature, alternate contact and left-hand winding of relay 34, normal contact and armature of relay 25, and conductor 44 to conductor 21. The party at station A would now depress the local key of the desired station, in this case key B, to signaling position. This would release his trunk key T without, however, operating the disconnect signal at the exchange and would also operate the signal 15 at B. The circuit through relay 23 will be opened when key T of station A is released and its armature will accordingly return to normal position. Key B would then be released to intermediate position, connecting the receiver and transmitter of station A to the line conductors 45 and 46 of station B. On hearing his signal 15 the party at B would depress his home button H to intermediate position and remove his receiver from the hook switch, thereby connecting his transmitter and receiver to the line conductors thereof and completing a talking circuit therebetween, talking battery 17 being

supplied to the circuit through the impedance coil 16 of station B and the conductors 45 and 46.

A would inform B of the trunk call and then hang up, severing his connection with B and being free to make or receive other intercommunicating calls. B would keep his receiver off and depress his key T to intermediate position, thereby operating relay 25 over a circuit extending from the exchange talking battery through ring contact 22, exchange end of conductor 21', conductor 42, left-hand contact of relay 34, conductor 47, armature and normal contact of relay 23 (thereby short-circuited), conductor 24, winding of relay 25, conductor 21', conductor 26 of station B, first and second contacts of key T, conductors 27, 28, transmitter, receiver and hook switch thereof, conductors 29 and 30, fourth and third contacts of key T, conductors 31 and 21 and tip contact 32 to the exchange talking battery. Relay 25 is thereby operated, opening the holding circuit of relay 34, which thereupon returns to normal, opening in turn the short circuit about the relay 23, and including this relay in the circuit just traced. Relay 23 will be actuated thereby and shunt out relay 25, the armature of which will thereupon return to normal, which places the trunk apparatus in the same condition that existed before the call was transferred. On completion of conversation, B would hang up, opening the circuit through relay 23, whereupon the system would be restored to normal condition, as previously explained.

When a trunk call is originated by an intercommunicating station, the trunk key T thereat is depressed to talking position and the receiver removed from the hook, thereby completing a signaling circuit to operate the answering signal 11 at the exchange. This circuit is identical with the talking circuit previously traced except that the answering signal 11 is included in circuit with the battery 50 through the normal contacts of the conductors 48 and 49 of jack 10. The signal 11 is thereby actuated, and the operator on plugging into the jack in answering would disconnect the signal 10 and battery from the trunk conductors 21 and 21' and substitute talking battery (not shown) therefor. On learning the party desired, the operator would complete the connection thereto and supervise the call in the usual manner. The relay 23 would be energized on signaling the exchange, and also after the operator has connected therewith in answering and would remain in this condition until the calling subscriber completes conversation and hangs up his receiver as previously explained.

What is claimed is:

1. In a telephone system, in combination, a subscriber's station, a trunk circuit to said

- station, a telephone set at said station adapted to be connected with said circuit, a bridging connection adapted when established to hold said circuit in substitution of said telephone set, a plurality of sources of current, and electromagnetic means initially energized by current from one of the sources to establish said bridging connection and maintained energized by current from another of the sources; the means having a winding included in said connection on establishment thereof to maintain said bridging connection. 5
2. In a telephone system, in combination, a subscriber's station, a trunk circuit to said station, a source of current for the trunk circuit, a telephone set at said station adapted to be connected with said circuit, a bridging connection adapted when established to hold said circuit in substitution of said telephone set, another source of current independent of the trunk circuit, a relay energized by current from such other source to establish said bridging connection and having a winding included in said connection on establishment thereof to maintain the relay energized by current from the first mentioned source to maintain said bridging connection. 10
3. In a telephone system, in combination, a plurality of subscribers' stations, a trunk circuit common to said stations, a telephone set at each station adapted to be connected with said circuit, a bridging connection adapted when established to hold said circuit in substitution of a telephone set, a plurality of sources of current, electromagnetic means initially energized by current from one of the sources to establish said bridging connection and maintained energized by current from another of the sources; the means having a winding included in said connection on establishment thereof to said bridging connection, and means to disable said bridging connection due to subsequent connection of one of the telephone sets with said trunk circuit. 15
4. In a telephone system, in combination, a plurality of subscribers' stations, a trunk circuit common to said stations, a telephone set at each station adapted to be connected with said circuit, a bridging connection adapted when established to hold said circuit in substitution of a telephone set, a plurality of sources of current, a relay initially energized by current from one of the sources to establish said bridging connection and maintained energized by current from another of the sources, said relay having a winding included in said connection on establishment thereof to maintain said bridging connection, and means to disable said bridging connection due to subsequent connection of one of the telephone sets with said trunk circuit. 20
5. In a telephone system, in combination, a subscriber's station, a trunk circuit incoming to said station, a telephone set at said station, means for connecting said telephone set with said trunk circuit, a key, a plurality of sources of current, a relay having a plurality of windings initially energized by current from one of the sources upon the actuation of said key over a circuit including one winding thereof, and a bridging connection including another winding of said relay and another of the sources of current established due to energization thereof for holding said trunk circuit in substitution of said telephone set. 25
6. In a telephone system, in combination, a plurality of subscribers' stations, a trunk circuit common to said stations, a telephone set at each station adapted to be connected with said circuit, a bridging connection adapted when established to hold said circuit in substitution of a telephone set, a plurality of sources of current, electromagnetic means initially energized by current from one of the sources to establish said bridging connection and having an energizing winding included in said connection on establishment thereof to maintain said bridging connection by current from the other of the sources, switching means at said stations to control the initial energization of said electromagnetic means, and means to disable said bridging connection due to subsequent connection of one of the telephone sets with said trunk circuit. 30
7. In a telephone system, in combination, a plurality of subscribers' stations, a trunk circuit common to said stations, a source of current associated with said circuit, a telephone set at each station adapted to be connected with said trunk circuit, a second source of current independent of the trunk circuit, a bridging connection adapted when established to hold said trunk circuit in substitution of a telephone set, a relay energized by current from the second source to establish said bridging connection, and a locking circuit for said relay established due to completion of said bridging connection and including said first source of current. 35
8. In a telephone system, in combination, a plurality of subscribers' stations, a trunk circuit common to said stations, a source of current associated with said circuit, a telephone set at each station adapted to be connected with said trunk circuit, a bridging connection adapted when established to hold said trunk circuit in substitution of a telephone set, a second source of current, a relay energized by current from the second source to establish said bridging connection, a locking circuit for said relay established upon the completion of said bridging connection and including said first source of current, switching means to connect a telephone set 40

with said trunk circuit, and a second relay operating due to actuation of the switching means to disable said locking circuit.

9. In a telephone system, in combination, 5 a plurality of subscribers' stations, a trunk circuit common to said stations, a source of current associated with said trunk circuit, a telephone set at each station, a trunk key at each station operable to control the connection of the telephone set thereat with said trunk circuit, a holding key at each station, a bridging connection adapted when established to maintain the circuit continuity of said trunk circuit in substitution of a telephone set, a second source of current, a relay energized upon the actuation of one of the holding keys by current from the second source, to establish said bridging connection across said trunk circuit, a locking 10 circuit established for said relay upon the energization thereof and including said first source of current, and a second relay operating due to subsequent actuation of a trunk key to disable said locking circuit.
10. In a telephone system, in combination, 20 a plurality of telephone stations, a trunk circuit common to said stations, a telephone set at each station adapted to be connected to said trunk circuit, a relay associated with said trunk circuit and operated on association of a telephone set with said trunk circuit, a bridging connection adapted when established to hold said trunk circuit in substitution of a telephone set, a second relay 30 inoperative during the energization of said first relay and operable to disable said bridging connection, electromagnetic means initially energized to establish said bridging connection and held energized through such connection due to establishment thereof, switching means at said station to actuate said electromagnetic means, means to disable said first relay upon the subsequent disconnection of a telephone set from said trunk 40 circuit, and means to actuate said second relay due to subsequent connection of a telephone set with said trunk circuit to disable the bridging connection.

11. In a telephone system, in combination, 50 a plurality of telephone stations, a trunk circuit common to said stations, a telephone set at each station adapted to be connected to said trunk circuit, a relay associated with said trunk circuit and operated on association of a telephone set with said trunk circuit, a bridging connection adapted when established to hold said trunk circuit in substitution of a telephone set, a second relay 55 inoperative during the energization of said first relay, switching means at a station, electromagnetic means initially energized due to actuation of the switching means to establish said bridging connection and held energized through such connection due to establishment thereof, means to disable said

first relay due to subsequent disconnection of a telephone set from said trunk circuit, means to prevent reenergization of said first relay while said electromagnetic means is energized, and means to actuate said second relay due to subsequent connection of a telephone set with said trunk circuit to disable the bridging connection. 70

12. In a telephone system, in combination, 75 a plurality of telephone stations, a trunk circuit common to said stations, a telephone set at each station adapted to be connected to said trunk circuit, a first relay in series with said trunk circuit and energized due to connection of a telephone set with said circuit, a second relay connected in series with the first and short-circuited by the energization of the first, a bridging connection adapted when established to hold said trunk circuit in substitution of a telephone 80 set, switching means at said stations, electromagnetic means initially energized due to actuation of the switching means to establish said bridging connection and held energized through such connection due to establishment thereof, means for deenergizing said first relay due to subsequent disconnection of a telephone set from said trunk circuit, a short circuit about said first relay partially established by the energization of said electromagnetic means and completely established due to subsequent deenergization of said first relay, and means to actuate said second relay due to subsequent connection of a telephone set with said trunk circuit to disable said bridging circuit and to deenergize said electromagnetic means. 90

13. In a telephone system, in combination, 95 a plurality of telephone stations, a trunk circuit common to said stations, a telephone set at each station adapted to be connected to said trunk circuit, a first relay in series with said trunk circuit and energized due to connection of a telephone set with said circuit, a second relay connected in series with the first and short-circuited by the energization of the first, a bridging connection adapted when established to hold said trunk circuit in substitution of a telephone set, a key, a third relay initially energized due to actuation of the key to establish said bridging connection and held energized through said connection due to establishment thereof, means for deenergizing said first relay due to subsequent disconnection of a telephone set from said trunk circuit, a short circuit about said first relay prepared by the energization of said third relay and completed due to subsequent deenergization of said first relay, and means to actuate said second relay due to subsequent connection of a telephone set with said trunk circuit to disable said bridging circuit and to deenergize said third relay. 100

14. In a telephone system, in combination, 110

5 a plurality of subscribers' stations, a trunk circuit common to said stations, a telephone set at each station for connection with said circuit, a bridging connection arranged on establishment to hold said circuit in substitution of a telephone set, means for establishing said bridging connection, means for disabling said bridging connection, and means responsive to the connection of the 10 telephone set of a station with the trunk circuit to prevent operation of said disabling means until after establishment of said bridging connection.

15 15. In a telephone system, in combination, a plurality of subscribers' stations, a trunk circuit common to said stations, means to operatively associate said stations with said trunk circuit, a bridging connection arranged on establishment to hold said circuit 20 in substitution of a subscriber's station, means for establishing said bridging connection, means for disabling said bridging connection, and means responsive to the operative connection of a station with the 25 trunk circuit to prevent operation of said disabling means until after establishment of said bridging connection.

16 16. In a telephone system, in combination, a plurality of subscribers' stations, a trunk 30 circuit common to said stations, means to operatively associate said stations with said trunk circuit, a bridging connection arranged on establishment to hold said trunk circuit in substitution of a subscriber's sta-

tion, means to establish said bridging connection, a relay to disable said bridging connection, a second relay responsive to the operative connection of a station with the trunk circuit to prevent operation of said first relay, and means operated subsequent 40 to the disconnection of said station from the trunk circuit and incident to the establishment of said bridging connection to render said second relay ineffectual to prevent subsequent operation of the first relay. 45

17. In a telephone system, in combination, a plurality of subscribers' stations, a trunk circuit common to said stations, means to operatively associate said stations with said trunk circuit, a bridging connection arranged 50 on establishment to hold said trunk circuit in substitution of a subscriber's station, means to establish said bridging connection, a relay to disable said bridging connection, a second relay responsive to the operative 55 connection of a station with the trunk circuit to short-circuit the first relay, and means operated subsequent to the disconnection of said station from the trunk circuit and incident to the establishment of the bridging 60 connection to short-circuit said second relay to render it ineffectual to prevent subsequent operation of the first relay.

In witness whereof I hereunto subscribe my name this 18th day of March, A. 65 D. 1918.

CHARLES W. KECKLER.
